ELECTRICAL MUSICAL INSTRUMENT

Laurens Hammond, Chicago, Ill.

Application July 24, 1940, Serial No. 347,265

14 Claims.

(CL 34—1.17)

My invention relates generally to electrical musical instruments, and more particularly to improved keying circuits for such instruments whereby new and interesting musical results may be obtained.

It is an object of my invention to provide an electrical musical instrument having a manual and a single pedal, wherein the single pedal is operative to cause playing of a note different from but related to the lowest note being played on the manual.

A further object is to provide an improved electrical musical instrument having a relatively small number of frequency sources which can be played easily by a pianist without necessitating learning of a pedal technique, to produce rich, full organ music.

A further object is to provide an improved keying circuit for electrical musical instruments in which the contemporaneous closure of two switches is required to cause sounding of a note, and in which one of the switches is controlled by a manual key, while the other switch is controlled by a pedal.

A further object is to provide a simple electric organ which may be manufactured at low cost, and which will adequately serve as a practical instrument for the playing of hymns and similar relatively simple musical selections.

Other objects will appear from the following description, reference being had to the accompanying drawings in which:

Figure 1 is a circuit diagram showing representative portions of the complete instrument;

Figure 2 is a circuit diagram illustrating a modified form of the invention; and

Figure 3 is a circuit diagram of a further modified form of the invention.

For the rendition of hymns and similar liturgical selections, it is not essential that an organ have available a variety of tone colors, or that its manual have a range as great as that of a standard organ. A statistical survey of a number of hymnals shows that the range of notes scored in hymns seldom, if ever, are above the note B4 (987.77 c. p. s.) or notes below C1 (65.406 c. p. s.), so that a four octave manual covering the note range from C1 to B4 is fully adequate for the rendition of this type of music.

In playing hymns and the like, a proficient organist will almost invariably play such selections using "full organ" registration, especially when the selections are played as accompaniment for congregation or choir singing.

Despite the fact that hymns are ordinarily not

scored with notes below the note C1, the experienced organist will almost invariably use the pedals to provide a bass accompaniment for the music as scored, and such bass accompaniment notes will usually be one or two octaves below the lowest note scored in the bass clef. Such pedal accompaniment adds greatly to the musical effect, and is one of the main characteristics (in addition to intensity or volume) which distinguishes pipe organ and full electric organ music from reed organ music, when the instruments are being used for the rendition of liturgical music.

Furthermore, in many small churches and similar institutions, there is not available within the means of the congregation, a trained organist, and the playing of the organ is usually delegated to a pianist who is not skilled in the pedal technique or in the registration which are necessary for competently playing an organ. The use of a pipe organ or full electric organ is therefore limited by the lack of trained organists.

These factors are conducive to the conclusion that many a small church, or the like, would have its musical requirements fully satisfied by a small electric organ limited in pitch range and tone colors available, but which would produce the low bass note accompaniment characteristic of standard pipe and electric organs without requiring the organist to be skilled in organ pedal technique or organ registration. The instrument described and claimed herein admirably fulfills these requirements, namely, simple construction, low cost, sufficient range to render liturgical music, bass pedal accompaniment effects, without requiring a pedal technique, and omission of register controls, which latter are not necessary for the rendition of liturgical music and which are frequently misused by unskilled organists.

Briefly, the invention comprises a keying system for instruments of the organ type in which a single pedal operated switch is provided to control the sounding of a note which is harmonically related to the lowest note represented by the depressed keys in the bass register of the manual. The pedal is spring-returned and thus does not operate as an organ stop, but is the means for controlling the sounding of the harmonically related note which may be, for example, one octave or two octaves below the lowest note of a chord being played in the bass register of the manual.

The invention differs fundamentally from the so-called "melody-octave-coupler" arrangements sometimes employed in pipe organs, in that the

player may easily control the sounding of the pedal note, determine the duration of the pedal note independently of the duration of the lowest note being played on the manual, and because the manual playing technique is not rendered difficult as it is when the melody-octave-coupler of a pipe organ is used. In the latter instance, the player must be very careful when playing a chord to make certain that the highest key of the chord is depressed slightly prior to the remaining keys, and is the last of the keys of the chord to be released. This technique required for the playing of the pipe organ using a melody-octave-coupler is difficult to acquire, and even a very skilled organist will, in endeavoring to use this technique, frequently fail to depress the highest key of the chord before the other keys are depressed, or to release the highest key of the chord only after the other keys have been released. Such failure results in the sounding of an arpeggio of undesired notes, which is very disturbing to the musician as well as to his audience.

As distinguished from this difficult technique required in playing pipe organs equipped with melody-octave-couplers, the musician playing on an instrument incorporating my invention need merely "beat time" upon a single pedal with his foot as he plays the selection in an otherwise normal manner, and by so doing he will control the sounding of the harmonically related pedal tone. Furthermore, the musician, while holding a given chord on the manual, may cause repetition of the pedal note merely by repeatedly depressing the pedal. Similarly, the pedal note may be sounded or not sounded with the base chord of the manual merely by operating, or refraining from operating, the pedal.

As shown in Fig. 1, the instrument comprises a manual consisting of a plurality of keys 10, which, in Fig. 1, also bear their respective note designations C1 to E1, C2[#], D2, B2, C3, and B4, these keys being representative of the complete series of keys from C1 to B4. There is likewise diagrammatically shown, a plurality of electrostatic generators, generating impulses of the fundamental frequencies of the keys C0 to B4 inclusive. Each of the generators comprises a wheel 12 and an electrode 14, the note pitch designation corresponding to the note frequencies which the wheels are designed to produce, being indicated upon each wheel. It will be understood that electrostatic generators are shown merely for the purposes of illustration, and that any other suitable electrical frequency or sound generating system may be employed. In the circuit of Fig. 1, as distinguished from the circuit of Fig. 3, hereinafter to be described, the generators, or parts associated therewith, must be of such character that the sounding of the tones generated may be controlled by a direct current potential upon an element forming a part of, or associated with, each of the generators.

Each of the keys is adapted to operate a single-pole single-throw switch arm 16 which is adapted, upon depression of the key, to engage a bus bar 18, the bus bar 18 being connected to an adjustable potential direct current source shown as a battery 20. The bus bar 18 may be common to all of the keys of the manual or may be made in sections, the potentials of which may be separately adjusted. The depression of any of the keys thus completes a circuit from the source 20 through the bus bar 18, its key switch 16, and its conductor 22 to an electrode 14 of the associated generator. The outputs of all of the genera-

tors are combined in a conductor 24 which is connected to ground through a load resistance 26, the potential changes across which are amplified in a preamplifier 28.

5 Tone and volume control devices 30 of any suitable design and arrangement receive the signal from the preamplifier 28, modify it as desired, and supply it to the power amplifier 32 which is connected to a loud speaker 34. Thus, 10 upon depression of any one of the keys 10 for the notes C2 to C6, the electrode 14 of its associated generator will have an energizing potential impressed thereon, but the connection between the conductor 22 and its electrode 14 is preferably such that the tone produced will have somewhat gradual attack and decay characteristics. This is accomplished by interposing 15 between the conductor 22 and its electrode 14, a network comprising a resistor R1 between the conductor 22 and electrode 14, and a resistor R2 and condenser C8 connected in parallel between the electrode 14 and ground. Thus, the rate at which the potential upon the electrode 14 20 is built up is determined primarily by the relative values of the resistor R1 and condenser C8, while the rate of decay of the note is determined by the relative values of the condenser C8 and resistor R2.

The keys 10 for the two lowermost octaves 30 of the keyboard are each adapted to operate a single-pole double-throw switch in addition to and simultaneous with the operation of their switches 16. Each of the single-pole double-throw switches comprises a switch arm 36, an 35 upper contact 38, and a lower contact 40. The switch arm 36 for the note C1 is connected by a conductor 42 to a switch 44, which is arranged to be closed upon the depression of a single bass pedal 46, the switch 44 being connected to an adjustable direct current potential source illustrated as a battery 48. The pedal 46 is diagrammatically illustrated as being pivoted, and provided with a return spring 49. The remaining switch arms 36 are each connected to the upper 45 contact 38 of the switch for the next adjacent lower note, so that when none of the keys is depressed, all of the upper contacts 38 of the switches will be interconnected by the switch arms 36.

50 Each of the lower contacts 40 is connected to an electrode 14 of a generator generating a frequency one octave or two octaves below that of the note designation of its key. Thus, the key 10 for the notes C1[#] and C2[#] have their lower 55 switch contacts 40 connected to the generator 12 for the note C0[#]. The connection between the lower contact 40 and electrode 14 is preferably through a resistance and capacity network which may comprise a series resistor R3, a shunt resistor R4 connecting the contact 40 to ground, and a condenser C9 connected between the electrode 14 and ground.

56 From the foregoing it will be apparent that whenever any keys from C1 to B2 is depressed, the lowermost of the keys within this range which is depressed will, through its switch arm 36, connect its lower contact 40 to the polarizing potential source 48 provided the bass pedal 46 is depressed. All of the switch arms 36 of 60 the depressed keys, other than the lowermost key depressed, will be ineffective because of the series arrangement of the single-pole double-throw switches.

65 The rate of attack of the tones produced by the generators 12 for the notes C0 to B0 will be

determined by the relative values of the resistor R₃ and condenser C₉, while the rate of decay will be determined by the sum of the resistances R₃ and R₄ relative to the value of the condenser C₉.

It will be noted that while two octaves of the keys of the manual, namely, C₁ to B₂, are capable of controlling the production of a bass pedal accompaniment note, only one octave of bass note generators is provided, and that therefore the lower contacts 40 for corresponding notes in the two lowermost octaves of the manual are connected respectively to a common generator. For example, it will be noted that the lower contacts 40 for the keys C₁ and C₂ are both connected to the electrode 14 for the generator which generates impulses at a pitch of C₀, and similarly, the lower contacts 40 for the keys D₁ and D₂ are both connected to energize the generator of pitch D₀.

Of course if desired, any other suitable arrangement of the connections from the lower contacts 40 to the generators could be utilized. For example, the lowermost contacts 40 for the keys in the second lowermost octave could be connected to energize the generator for a note one octave lower instead of two octaves lower, e. g., the contact 40 for the key D₂ could be connected to the energizing circuit of the generator for note D₁.

In playing the instrument as in the rendition of a hymn, the selection will be played upon the manual keys 10 in the usual manner, and the player will, whenever a bass accompaniment note is desired, depress the bass pedal 46. Depression of this pedal 46 will automatically cause sounding of a bass note one or two octaves below the lowest note of the keys depressed on the manual (providing such lowest note is within the range C₁ to B₂), thus providing an adequate bass accompaniment which, in most instances, will be identical with that which the player might use if he had a full range of organ pedal notes available. In order to prevent the sounding of unwanted notes, the player will preferably depress the bass pedal 46 for each bass note desired. If this were not done, it is possible that the player might not release the keys on the manual simultaneously, and if the lowermost key depressed were released before other keys (within the range C₁ to B₂), such other keys would cause the sounding of their associated bass accompaniment notes. Thus, in the preferred method of playing the instrument, the pedal will be depressed an instant after the manual keys have been depressed, and the pedal released an instant before the manual keys are to be released. When the instrument is played sufficiently rapidly, e. g. from one chord to the next, the bass note of the first chord may not have decayed to inaudibility before the bass note of the next chord is sounded, thus providing a legato type of bass accompaniment even though it is obviously impossible to operate the bass pedal in a legato manner.

It will be understood that it is not essential that the generators controlled by the single-pole double-throw key switches be one or two octaves below, but merely that they be harmonically related to the pitches of the keys by which they are controlled.

From the foregoing it will appear that I have provided a very simple form of electrical musical instrument capable of the rendition of customary liturgical music in a conventional organ-like manner, without the necessity of providing

the usual pedal clavier, and without making it necessary for the player to acquire pedal technique or to become proficient at organ registration. It will be understood that the generators employed are preferably such as will produce a tone characteristic of "full organ," so that the music produced in the playing of hymns and the like, will be the equivalent of that which would be produced by a relatively large and expensive organ when registered for the playing of liturgical music. To further this result, the generators may be designed to produce complex tones, each containing not only the harmonic partials of the 8 ft. pitch, but also some of the harmonics of the 4 ft. pitch, or the 16 ft. pitch, or both.

In Fig. 2, I have disclosed representative portions of an instrument employing a slightly modified circuit. Such elements of the modification of Fig. 2 which are similar to those previously described, have similar reference characters applied thereto and will not be again described. The adjustable direct current potential source 48 is connected by a current limiting resistor R₅ to ground through a normally closed switch 56, which is adapted to be opened upon depression of the bass pedal 46. The resistor R₅ is also connected between conductor 42 and the potential source 48 so that when the bass pedal is depressed, the potential from the source 48 will be impressed upon the conductor 42, and thus be available for the energization of the bass tone generators. The modification shown in Fig. 2 will be played in a manner as described above with reference to the construction shown in Fig. 1.

In Fig. 3 I have illustrated the invention as applied to an electrical musical instrument in which the tones are controlled by keying signals produced by continuously operating generators. The diagram of Fig. 3 is thus representative of the application of the invention to electrical instruments in which signal generators are employed, and in which the output of the generators is transmitted to the output circuit of the instrument under the control of key operated switches, as distinguished from the construction shown in Figs. 1 and 2, wherein the outputs of the generators are controlled by key operated switches controlling energizing circuits for the generators.

Such of the elements of the modification of Fig. 3 which are similar in construction and function to parts previously described, have had corresponding reference characters applied thereto.

The signal generators comprise tone wheels 52 made of magnetic material and having projections on their peripheries rotating in close proximity to wedge-shaped ends of permanent magnets 54 in a manner similar to that disclosed in my aforesaid Patent No. 1,956,350. For the present purposes, however, the peripheries of the tone wheels 52 are formed to produce a complex wave form of considerable harmonic development.

Generators C₁ to E₁, C₂, D₂, B₂, B₃, and B₄ are shown as representative of a complete set of generators for the notes C₁ to B₄ while generators C₀ to E₀ and B₀ are illustrated as representative of the twelve pedal tone generators for generators for the notes C₁ to B₄, while generators has a winding 58 around its permanent magnet 54, one end of the winding being grounded, while the other end is connected through a current limiting resistance 58 to its associated key operated switch 16. The key operated switches 16 are adapted to make contact with a

bus bar 60 which is connected by a conductor 52 to a selected one of a plurality of taps on a primary winding 64 of an output transformer 66, the secondary 68 of which is connected to a tone and volume control apparatus 10, and thence through a preamplifier 72 and power amplifier 74 to a loud speaker 76.

Upon depression of any one of the keys 10, a signal from its associated generator will be transmitted to the output circuit, amplified, and translated into sound. Each of the keys, in addition to operating its switch 16, operates its associated switch arm 36. As will be apparent, these keys are so arranged that the lowest of a plurality of depressed keys will select a generator either one 15 octave or two octaves below the pitch of the lowermost depressed key, and connect its output to conductor 78. The conductor 78 is adapted to be connected through a conductor 79 to a selected tap on the primary 64, upon closure of a switch 80 20 operable by depression of a spring-returned pedal 82.

From the foregoing description it will be clear that the instrument illustrated in Fig. 3 will be operative to produce results similar to those obtained by the instrument shown in Figs. 1 and 2, namely, the sounding of a note, under control of the pedal 82, which is one or two octaves lower in pitch than the lowermost note being played on a given section of the manual. The relative intensities of the tones produced under the control of the manual and those produced under the control of the pedal 82, may readily be controlled by the selective connection of the conductors 62 and 79 to different taps on the transformer primary 64.

In the embodiments illustrated and described herein, the circuit arrangement is, in each instance, of a type such that the lowermost of a plurality of keys depressed controls the pitch of the tone controlled by the pedal. It will be clear that the arrangement of the single-pole double-throw switches operated by the keys could readily be reversed so that the highest depressed key of the manual would control the pitch of the tone produced by depression of the pedal. Such latter arrangement might be of musical usefulness in some instances, although in the majority of cases, the arrangement disclosed will be more useful.

As previously intimated, the generators may be of any suitable type which may be energized under the control of the playing keys, or the output of which may be controlled by the playing keys. Representative generators of this class are disclosed in my prior applications Serial No. 157,969, filed August 7, 1937 and Serial No. 281,077, filed June 26, 1939, or in any one of the following patents: Nos. Re. 21,137, 2,126,464, 2,126,682 and 1,956,350. In their broader aspects, the principles of my invention may also be applied to instruments having an electrically controlled sound generator for each note.

It will be further understood that while in the preferred form of the invention the accompaniment tone is one which is an octave or two octaves below the lowermost of the bass register manual keys depressed, the principles of the operation of the invention may also be employed in a manner such that a note higher than the highest depressed key on the manual, but harmonically related thereto, will be sounded. The underlying principle of the invention is that an additional manually or pedal operated control is provided which, when operated, will cause the production of a note which differs from, but is harmonically

related to, a note produced by depression of a key of the manual.

While I have shown and described particular embodiments of my invention, it will be apparent to those skilled in the art that numerous variations and modifications are possible without departing from the underlying principles of the invention. I therefore desire, by the following claims, to include within the scope of my invention, all such variations and modifications by which substantially the results of my invention may be obtained by substantially the same or similar means.

I claim:

1. In an electrically controlled musical instrument, the combination of a manual having a plurality of depressible keys, a musical tone generating system controlled by said keys, an accompaniment tone generating system, means controlled by the endmost of a plurality of simultaneously depressed keys of said manual to select the pitch of the tone to be produced by said accompaniment tone generating system, a single normally ineffective control element, and means operated by said control element to render said accompaniment tone generating system effective to produce the tone of selected pitch.

2. In an electrically controlled musical instrument, the combination of a manual having a plurality of depressible keys, a musical tone signal generating system controlled by said keys, an accompaniment tone generating system, means controlled by the lowermost of a plurality of simultaneously depressed keys of said manual to determine the pitch of the tone to be produced by said accompaniment tone generating system, a pedal, and means operated by said pedal to render operative said accompaniment tone generating system.

3. In an electrical musical instrument, the combination of a manual comprising a plurality of keys, a tone generating system controlled by said keys, a plurality of accompaniment tone generators of pitch lower than that represented by the lowest key of said manual, means operated by the lowermost of a plurality of said keys which are simultaneously depressed to select one of said accompaniment tone generators for operation, a pedal, and means operated by said pedal for rendering the selected tone generator effective to produce its tone.

4. In an electrical musical instrument, the combination of a manual comprising a plurality of keys, means controlled by said manual for producing musical tones, means for generating accompaniment tones, means operated by said keys to determine which of said accompaniment tone generators is to be rendered operative, a bass pedal, and means controlled by said bass pedal to render operative the tone generator selected by said keys.

5. In an electrical musical instrument, the combination of a manual comprising a plurality of keys, means for generating tones corresponding respectively to the keys of said manual, means for generating tones of pitch beyond the range of said manual, a control element for said additional generators, resilient means to maintain said control element in ineffective position, and means conjointly controlled by said manual keys and said control element to cause sounding of one of said additional generators.

6. In an electrical musical instrument, the combination of a manual comprising a plurality of keys, means controlled by depression of said

keys to cause sounding of notes corresponding to the keys, a single bass pedal, means biasing said pedal toward an ineffective position, and means operated by said pedal to control the sounding of a note which differs in pitch from but is harmonically related to the note corresponding to the lowermost of the depressed keys of said manual.

7. In an electrical musical instrument, the combination of a manual comprising a plurality of keys, means controlled by said keys to cause the sounding of notes corresponding in pitch to said keys, a bass accompaniment control element, and means conjointly controlled by said element and the lowermost of any of a plurality of keys depressed on said manual to cause the sounding of a note harmonically related to but lower in pitch than the note corresponding to said lowermost depressed key.

8. In an electrical musical instrument having an output circuit, a manual comprising a plurality of keys and a signal generating system controlled by said keys, an accompaniment tone generating system, a single pedal, and means controlled conjointly by said pedal and said keys to cause transmission to the output of the instrument of a tone signal from said accompaniment tone generating system.

9. In an electrical musical instrument, the combination of a manual including a plurality of keys, a signal generating system controlled by said keys, a series of single-pole double-throw switches operable respectively by keys of said manual, a plurality of accompaniment generators, means controlled by said switches for selecting one of said accompaniment generators, a bass pedal, and a circuit controlled by said bass pedal to render effective the generator selected by said selecting means.

10. For use in an electrical musical instrument having an output circuit and a plurality of generators of electrical impulses of musical frequencies, a plurality of keys forming a manual, circuits completed by operation of said keys to cause transmission to the output circuit of the instrument of electrical impulses of frequencies corresponding to the operated keys, an additional set of electrical generators, a slow decay circuit associated with each of said generators of said additional set, means operated by said keys to select one of the generators of said additional set which is harmonically related to the lowest of a plurality of said keys which are simultaneously depressed, a foot-operated pedal, means to bias said pedal to inoperative position, and a circuit completed upon operation of said pedal to cause the transmission to said output circuit of impulses from the generator of said additional set which has been selected by said key operated means.

11. For use in an electrical musical instrument having an output circuit and a plurality of generators of electrical impulses of musical frequencies, at least twenty-four keys forming a manual, circuits completed by operation of said keys to cause transmission to the output circuit of the instrument of electrical impulses of fre-

quencies corresponding to the keys, an additional set of electrical impulse generators of frequencies lower than the frequency of any of said first named generators and lesser in number than the keys of said manual, a slow decay circuit associated with each of said additional generators, means operated by said keys to select one of said additional generators which generates a frequency one or more octaves lower than the frequency associated with the lowest of a plurality of said keys which are simultaneously depressed, a foot-operated spring-returned pedal, and means rendered effective by operation of said pedal to cause transmission to said output circuit of impulses from the one of said additional generators which has been selected by said keys.

12. For use in an electrical musical instrument having a plurality of keys, a plurality of electrostatic generators, and attack and decay circuit elements for each of said generators, the combination of means controlled by each of said keys for impressing an exciting potential on the generator associated therewith through its attack and decay circuit elements, a conductor, means controlled by the lowest of a plurality of simultaneously depressed keys to connect said conductor to the attack and decay circuit elements of one of said generators of a frequency one or more octaves lower than the frequency represented by said lowest key, a source of exciting potential, a foot-operated spring-returned bass pedal, and a switch operated by said pedal effectively to impress the potential of said source upon said conductor.

13. For use in an electrical musical instrument having an output circuit and a plurality of electromagnetic generators of electrical impulses of musical frequencies, a plurality of keys forming a manual, circuits completed by operation of said keys to connect selected generators to the output circuit of the instrument, an additional set of electromagnetic generators of lesser number than the keys of said manual, means operated by said keys to select one of the generators of said additional set which is harmonically related to the lowest of a plurality of said keys which are simultaneously depressed, a foot-operated pedal, means to bias said pedal to inoperative position, and a circuit completed upon operation of said pedal to connect to said output circuit the generator of said additional set which has been selected by said key operated means.

14. In an electrically controlled musical instrument, the combination of a manual including a plurality of keys, a signal generating system controlled by said keys, switches operable respectively by keys of said manual, a plurality of accompaniment generators, means controlled by said switches for selecting one of said accompaniment generators, a bass pedal, a circuit controlled by said bass pedal to render effective the generator selected by said selecting means, and means to bias said bass pedal to ineffective position.

LAURENS HAMMOND.

CERTIFICATE OF CORRECTION.

Patent No. 2,241,363.

May 6, 1941.

LAURENS HAMMOND.
